FOLDING CHAIR

Roy Campbell Thomson, London, England

Application January 28, 1937, Serial No. 122,752
In Great Britain February 21, 1936

7 Claims. (Cl. 155—177)

This invention relates to folding chairs and is especially applicable to chairs comprising a pivoted X-shaped frame and generally known as deck chairs.

According to the invention there is provided in or for a deck chair, a head-rest comprising side-supports hinged or adapted to be hinged on the chair-frame for adjustment backwards and forwards and an adjustable strut for engagement with the chair-frame to vary the position of the head-rest.

A feature of the invention consists in that the head-rest comprises two struts pivotally mounted, one on each of the side-supports and provided with spaced projections for engagement with the chair-frame, a flexible part extending between the side-supports and a cross-link connecting the struts at a position spaced away from their ends.

20 The pressure of the head on the flexible part of the head-rest draws the two side-supports towards one another so that, due to the provision of the cross-link the outer ends of the struts are moved outwardly away from one another, so that 25 their projections engage with the co-operating projections on the chair-frame, to hold the head-rest in position. The movement of the two side-supports towards one another is conveniently permitted by reason of slight play in the pivotal 30 mounting of these supports or the resilience of the supports themselves.

According to a feature of the invention there is provided the combination of a folding chair and a head-rest comprising side-supports pivotally mounted on the chair-frame for adjustment of the position of the head-rest, a flexible part extending between these side-supports, a pair of rearwardly-extending struts pivotally mounted, one on each of said side-supports, which strut 40 members are each provided with a plurality of outwardly-directed spaced projections for engagement with projections on the chair-frame and a cross-link connecting the struts at a position spaced away from their ends.

45 In a preferred construction, a fixed guide is provided on the chair-frame for each of the rearwardly-extending struts and means is preferably provided for locking the struts in the guides.

A feature of the invention consists in the combination with a chair having a head-rest as aforesaid, of a tent or like frame comprising two front pillars detachably mounted on side-members of the chair-frame and two rear pillars detachably mounted upon the side-supports of the 55 head-rest, which rear pillars are at least in part

flexible and are bent over and detachably connected to the upper ends of the front pillars. Preferably, a cross-bar is detachably connected to the upper ends of the front pillars and serves also to lock the ends of the rear pillars when connected therewith.

A further feature of the invention consists in the provision of a deck chair in which the head-rest aforesaid extends beyond the main frame, and the main frame is itself made correspondingly shorter. In this manner, the chair when folded is appreciably shorter than a deck chair of normal construction.

An embodiment of the invention is shown by way of example in the accompanying drawings, in which:

Figure 1 is a perspective view of a deck chair provided with a head-rest and tent frame;

Figure 2 is a view similar to Figure 1 with the tent cover in place;

Figure 3 is a side elevation of the head-rest in place on the chair;

Figure 4 is a plan of the head-rest viewed in the direction of the arrow 4 in Figure 3;

Figures 5 and 6 are diagrammatic views of the head-rest showing the manner of its operation;

Figures 7 to 10 show details of the tent frame;

Figure 11 is an elevation of a deck chair in which the head-rest extends beyond the main frame, and

Figure 11a is a detail thereof.

Like references indicate like parts in the several figures of the drawings.

Referring to Figures 1 to 4 of the drawings there is shown a deck chair of normal construction comprising two frame-parts 10 and 11 pivoted together, a stay-frame 12 pivoted to the frame-part 10 and a flexible seat 13 secured to opposite ends of the frame parts 10 and 11. On each side-member 10a of the frame-part 10, there is secured a bracket 14 conveniently of U-shape, the limbs of which bracket extend upwardly beyond the frame. Between the limbs of each bracket 14 there is pivotally mounted a side-support 15 of the head-rest, and a strip 16 of canvas, or other flexible material, is secured to the two side-supports 15.

On the inner side of each of the side-supports 15 there is pivotally mounted a strut 17 and each of these struts is provided with a plurality of 50 projections 18 for engagement with a projection 19 at the top and at the inner side of the frame-member 10a.

The struts 17 are arranged to slide on the normal top bar 21 of the frame-part 10, to which bar 55

the upper end of the flexible seat 13 is connected. Each strut is retained in position on the bar 21 by means of a guide consisting of a bracket 22 secured to the upper end of the frame-member 5 10a and overlying the strut 17.

In use, when no pressure is applied to the flexible part 16 of the head-rest, there is no effort to force any of the projections 18 into engagement with the co-operating projections 19 on the chair-frame, so that, as will be seen from Figure 5, the head-rest can easily be adjusted about the pivotal mounting of its side-supports. When pressure is applied to the flexible part 16 of the head-rest the several parts take up the positions shown 10 15 in Figure 6. The outer ends of the supporting side-members are drawn slightly together and thus the struts 17, pivoting about their connection to the cross-link 20, are forced outwardly at their outer ends to bring the projections 18 into engagement with the projections 19, the projections 18 which have effect being those next adjacent to the projections 19 in the selected position of the head-rest. Thus, the head-rest may be very 20 25 easily adjusted by the user while actually seated in the chair.

In order to prevent the struts 17 from being drawn clear of the bar 21, a stop 23 is provided on each of these struts to engage with the bracket 22. These stops 23 are hinged to enable them to be 30 folded flat against the strut 17 in order to permit the struts 17 to be withdrawn for folding up the chair. Thus, in the folded position of the chair the side-supports 15 of the head-rest can be turned either forwardly or backwardly down on to the side-members 10a of the frame, and the struts 17 are in turn folded down to lie just within the supports 15. Locking means consisting of a thumb-screw 24 screw-threaded in each of the guide-brackets 22 is conveniently provided rigidly to lock the struts in any selected position by clamping them against the frame-bar 21.

In order to provide for the attachment of the tent frame each of the side-members 11a of the frame-part 11 has secured to its forward end a plate 30 formed with a hole 31 having a key-slot 32 (see Figures 7 to 9). Two front pillars 33 are detachably connected to the plates 30 and for this purpose each pillar 33 is provided with a spigot 34 entering in the hole 31 and a lateral pin 35 40 which is passed through the slot 32 and is moved behind the plate 30 by turning the pillar 33, in order to retain the latter in position.

In the top of each of the side supports 15 of the head-rest there is secured a stirrup member 36 55 providing between the stirrup and the side-support 15 a socket to receive the lower part 37 of a rear pillar of the tent frame. The lower part 37 of each rear pillar is conveniently of rigid construction and is secured to an upper part 38 which 60 is flexible and is constructed for example of spring steel. The resilient part 38 of each rear pillar is bent over to engage under a strap 39 at the upper end of the corresponding front pillar 33. A cross bar 40 is provided to connect the 65 upper ends of the pillars and this cross-bar has at each end a right-angled portion 41 engaging in a hole in the end of the flexible part 38 of the rear pillar and in a staple 42 secured to the front pillar. The cross-bar 40 is preferably wider than 70 the chair so that the pillars 33 are splayed outwardly towards the top. The lower part 37 of each rear pillar is slightly twisted so that the upper flexible part 38 may readily be bent down to the upper ends of the front pillars. The tent frame thus provided is adapted to receive a tent 75

covering as indicated at 43 in Figure 2. The tent frame is thus easily assembled and dismantled and comprises when dismantled only a small number of parts which are all straight and can therefore be easily packed.

In a modification of the chair as shown in Figure 1, the head-rest is arranged to extend beyond the main frame and the main frame is itself made correspondingly shorter. For instance, as shown in Figure 11 the side-supports 15 of the head-rest are secured to extension strips 45 pivotally mounted on the side-members 12a of the stay-frame 12 of the chair. The struts 17 are pivoted to lateral extension brackets 15a (Figure 11a), secured to the side-supports 15 of the head-rest 15 in order that the struts may be folded within the frame part 10a in the folded position of the chair. The struts 17 engage with the top of the frame-members 10a, which in this instance, are shorter than is usual. In the lowest position of the head-rest 16 it is substantially co-extensive with the main seat 13 so that the total length of the chair may be at least as long as the normal construction of deck chair as shown in Figure 1. In the folded condition, however, the head-rest 16 folds 20 forwardly on to the frame-part 10 and the frame-part 11 can conveniently be of shorter dimensions without materially affecting the nature of the chair, i. e., of the same length as the shortened frame-part 10. A chair which is short and compact in the folded condition is thus provided.

I claim:—

1. In a chair, the combination with a chair frame, of a head-rest comprising side-supports, a flexible rest member extending between and carried by said side-supports, means for hinging said side-supports on the chair frame, two struts pivotally mounted at their forward ends one on each of said side-supports, a cross link pivotally connecting the said struts intermediate their ends, 40 engaging means on the outer sides of the rear ends of said struts, co-operating engaging means on said chair frame engaging said means on the struts, whereby pressure applied to the flexible rest member spreads the rear ends of the struts 45 apart to bring the engaging means thereon into engagement with the co-operating engaging means on the chair frame.

2. In a chair the combination with a chair frame of a head-rest comprising side-supports, a flexible rest member extending between and carried by said side-supports, means for hinging said side-supports on the chair frame, two struts pivotally mounted at their forward ends one on each of said side-supports and provided with outwardly-directed spaced projections at their rear ends for engagement with the chair frame, and a cross-link pivotally connecting said struts intermediate their ends.

3. In a chair comprising a folding chair frame 60 and a head-rest, the combination of head-rest side-supports pivotally mounted on said frame, a flexible rest member extending between and carried by said side-supports, a pair of rearwardly-extending struts pivotally mounted at their forward ends one on each of said side-supports, which struts are each provided at their rear ends with a plurality of outwardly-directed spaced projections, a cross link pivotally connecting said struts intermediate their ends, guides on said chair frame for receiving said struts and projecting means therein and means carried by said frame for engagement by the projections on said struts when pressure is applied to the flexible rest member.

4. A folding chair according to claim 3, comprising means for locking the struts in the said guides.

5. In a folding chair, the combination with a chair frame of a head-rest comprising side-supports pivotally mounted one on each side of the chair frame, a flexible rest member extending between said side-supports, a pair of rearwardly-extending struts pivotally mounted at their forward ends one on each of said side-supports, which struts extend within the chair frame and are each provided with a plurality of outwardly-directed spaced projections at their rear ends for engagement with the chair frame, a cross link pivotally connecting said struts intermediate their ends, means for locking said struts in fixed relation with the chair frame, two front pillars detachably mounted one on each side of the chair frame at the front of the chair, two rear pillars detachably mounted upon said side supports of the head-rest, which rear pillars are flexible for at least part of their length and are bent forwardly and means for detachably connecting the upper ends of the rear pillars to the upper ends of the front pillars respectively.

6. In a folding chair, the combination with a chair frame of a head-rest comprising side-supports pivotally mounted one on each side of the chair frame, a flexible rest-member extending between said side-supports, a pair of rearwardly-extending struts pivotally mounted at their forward ends one on each of said side-sup-

ports, which struts extend within the chair frame and are each provided with a plurality of outwardly directed spaced projections at their rear ends for engagement with the chair frame, a cross-link pivotally connecting said struts intermediate their ends, means for locking said struts in fixed relation with the chair frame, two front pillars detachably mounted one on each side of the chair frame at the front of the chair, two rear pillars detachably mounted upon said side supports of the head-rest, which rear pillars are flexible for at least part of their length and are bent forwardly to engage the upper ends of the front pillars respectively, and a cross-bar detachably connected to the upper ends of the front pillars.

7. In a chair the combination of a chair frame of a head-rest comprising two side-supports, means for hinging said side-supports on the chair frame for adjustment backwards and forwards, two struts pivotally mounted at their forward ends, one on each of said side-supports and provided at their rear ends with spaced abutments, a flexible member extending between the said side-supports and a cross-link pivotally connecting the struts intermediate their pivotal mounting and their rearward ends, said chair frame being provided with abutments engaged respectively by the said abutments on the two struts by relative outward movement of the rear ends of the struts.

ROY CAMPBELL THOMSON.
